Patented Feb. 28, 1922.

UNITED STATES PATENT OFFICE.

CHRIST CHRISTENSEN, OF KENOSHA, WISCONSIN.

DRAWER ATTACHMENT FOR BEDS.

1,408,269.

Specification of Letters Patent. Patented Feb. 28, 1922.

Application filed March 30, 1921. Serial No. 457,160.

To all whom it may concern:

Be it known that I, CHRIST CHRISTENSEN, a subject of the King of Denmark, residing at Kenosha, in the county of Kenosha and

5 State of Wisconsin, have invented certain new and useful Improvements in Drawer Attachments for Beds; and I do hereby declare the following to be a full, clear, and exact description of the invention, such as 10 will enable others skilled in the art to which it appertains to make and use the same.

The invention aims to economize space in living quarters and provide for the storage of apparel, bed clothing and other articles 15 usually placed in closets, wardrobes, bureaus and the like.

In close quarters, such as small apartments, space is at a premium and the present invention provides for the utilization 20 of such space to the best possible advantage.

Beds usually occupy a relatively large amount of room because of their extent and the space therebelow is ordinarily lost or if utilized receives boxes and other receptacles containing articles for future use. 25 The floor being thus occupied cannot be conveniently kept clean from lint, dust and kindred accumulations.

The present invention provides a drawer 30 and supporting means for attachment thereof to a bed whereby to utilize the space below the bed bottom without obstructing the floor to such an extent as to preclude the ready and convenient cleaning thereof.

35 Other objects and advantages will be apparent and suggest themselves as the nature of the invention is understood.

While the drawings illustrate an embodiment of the invention, it is to be understood 40 that in adapting the same to meet different conditions and requirements, various changes in the form, proportion and minor details of construction may be resorted to without departing from the nature 45 of the invention.

Referring to the accompanying drawings forming a part of the specification,

Figure 1 is a side view of a bed provided 50 with a drawer attachment embodying the invention,

Figure 2 is a transverse section of the bed, showing the drawer and supporting means in side view,

55 Figure 3 is a transverse section of the drawer and supporting means,

Figure 4 is a detail view of a hanger,

Figure 5 is a detail view of one of the drawer rests or slides, and

60 Figure 6 is a sectional detail on the line 6-6 of Figure 2.

Corresponding and like parts are referred to in the following description and designated in the several views of the drawings by like reference characters.

The bed illustrated is of the metal type 65 and has been selected because the invention is particularly designed for beds of this type.

The numeral 1 designates the side rails of the bed and said rails are of L-form in cross section. The supporting means for the 70

drawer embodies four hangers which are substantially alike in construction and arrangement, hence a detail description of one only will be given. Each of the hangers comprises complementary members 2 and 3 75

having adjustable connection whereby to adapt the attachment for different requirements. The member 2 is provided at its upper end with a hook 4 which engages over a rail 1. A bracket 5 is secured to the upper 80 portion of the member 2 and is disposed below the horizontal wing of the rail and acts jointly with the hook 4 to prevent displacement of the hanger after the parts have been placed in position. The members 2 and 85

3 preferably consist of straps or bars of metal and have corresponding openings 6 in their length to provide for lengthening or shortening of the hanger as conditions may require. Bolts 7 or analogous fastening 90 means secure the members 2 and 3 in the required adjusted position by passing through registering openings thereof. Bars 8 connect corresponding hangers upon opposite sides of the bed. These bars are adjustable to admit of ready adaptation of the attachment for different sized beds. The bars 8 are of sectional formation and each of the sections has a longitudinal slot 9 to receive a bolt 10 or other fastening whereby 95

100 to secure the sections in the required adjusted position.

Angle bars 11 are attached to the bars 8 and constitute rests or slides for the drawer. Hooks 12 are attached to the angle bars 11 105

and engage over the upper edge portions of the bars 8 and retain the angle bars in position. Tie bars 13 connect opposite angle bars 11 and hold them in proper position.

110 A drawer 14 is slidable on the horizontal wings of the angle bars 11 and is movable transversely of the bed and adapted to be

drawn outward from either side thereof. For this purpose, the drawer 14 is provided at each end with a handle 15. The drawer 14 is of a length corresponding to the width 5 of the bed. It will thus be understood that the same is spacious and adapted to receive wearing apparel without necessitating the folding of the same. A cover 16 extends over the top of the drawer and along opposite sides thereof and practically excludes dust, lint, and so forth from the drawer. The cover preferably consists of sheet metal 10 and the drawer 14 is made up of like material. It will thus be understood that all 15 the parts of the attachment are of metal and should occasion require, the parts may be stiffened or reinforced for durability and strength.

The invention provides an attachment 20 whereby space ordinarily lost is utilized to advantage for storing wearing apparel and bed clothing and sundry articles usually stored in wardrobes, bureaus, closets and the like. Moreover, the space below a bed bottom is utilized for storage purposes without 25 obstructing the floor and interfering with proper cleaning of the floor below the bed.

What is claimed is:

1. In a bed, means for supporting a

drawer beneath the bottom thereof comprising spaced bars, and drawer rests provided at intervals in their length with hooks for engaging over the upper edge portions of the bars and retaining the rests in position. 30

2. In a bed, means for supporting a drawer beneath the bottom thereof including bars, drawer rests supported by means of said bars, and tie members connecting said 35 rests and holding them in predetermined position. 40

3. In a bed adjustable hangers engaging the side rails thereof, adjustable bars connecting corresponding hangers upon opposite sides of the bed, angle bars constituting rests provided at intervals in their 45 length with hooks engaging over upper edge portions of said bars, tie members connecting the angle bars, and a drawer slidably mounted upon the horizontal wings of the 50 angle bars.

In testimony whereof I affix my signature in presence of two witnesses.

CHRIST CHRISTENSEN.

Witnesses:

HOLGER L. STANSGAARD,
CHRIS SORENSEN.
